SHOULDER PAD

Frank Schulman, Louisville, Ky.

Application September 3, 1946, Serial No. 694,475

4 Claims. (Cl. 2-268)

1

This invention relates to shoulder pads and while it is designed for use in various types of outer garments, it is intended primarily for use in the shoulder portions of women's clothing.

It is an object of the invention to provide a very light but strong pad which can be worn comfortably, will not cause discomfort during warm weather, and is especially useful for the purpose of equalizing the shoulders of the garment when it is worn by a person having one shoulder lower than the other.

A further object is to provide a pad which can be adjusted to meet the conditions under which it is worn, does not require the use of a filling pad, and maintains a flexible condition at all times.

Another object is to provide shoulder pads which can be quickly placed in or removed from a garment so that one pair can be used with a number of garments successively, the pads being removable when the garment is to be cleaned.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawings the preferred form of the invention has been shown.

In said drawing

Figure 1 is a perspective view of a portion of a garment equipped with one of the pads, portions of the garment being broken away.

Figure 2 is a perspective view of the pad.

Figure 3 is a vertical longitudinal section therethrough taken substantially on the line 3-3, Fig. 2.

Figure 4 is a perspective view of the blank from which the top or finishing piece of the shoulder pad is formed.

Figure 5 is a perspective view of the blank from which the top stiffening piece of the pad is to be formed.

Figure 6 is a perspective view of the blanks from which the lower or supplemental stiffening pieces are produced.

Figure 7 is a perspective view of the blank from which the stiffening band is to be shaped.

Figure 8 is a perspective view of a portion of the lining.

The principal parts of the shoulder pad are illustrated in Figs. 5, 6, 7 and 8. The blank illustrated in Fig. 5 is of substantially segmental form

2

and has been indicated at 1. It is made of a suitable stiffening fabric, such as buckram and has an elongated V-shaped slit 2 extending toward the apex 3 of the blank from the center of the broad end or base of the blank. This base edge can be arcuate and has wings 5 extending therefrom adjacent to opposite sides of the blank.

5 The lower or supplemental stiffening portion of the pad comprises two members 6 and 7 also formed preferably of buckram or the like. The member 6 is substantially segmental with an arcuate base edge 8 having short V-shaped slits 9 extending thereto from the base edge 8 and dividing the base or broad end portion of the member 6 into separate portions 10 forming wings.

A shallow V-shaped recess 11 is provided in the member 6 at the small end thereof. The member 7 is of a stiffening fabric such as buckram and has converging base edges 12 adapted to match the

15 edges of the recess 11. The side edges of the member 7 converge as indicated at 13 and extend to an abrupt V-shaped terminal portion 14.

A stiffening band 15 also formed preferably of buckram or the like constitutes another mem-

20 ber of the stiffening structure of the pad and has a V-shaped slit 16 extending thereto from one edge.

A stiffening band 15 also formed preferably of buckram or the like constitutes another mem-

25 ber of the stiffening structure of the pad and has a V-shaped slit 16 extending thereto from one edge.

A stiffening band 15 also formed preferably of buckram or the like constitutes another mem-

30 ber of the stiffening structure of the pad and has a V-shaped slit 16 extending thereto from one edge.

A stiffening band 15 also formed preferably of buckram or the like constitutes another mem-

35 ber of the stiffening structure of the pad and has a V-shaped slit 16 extending thereto from one edge.

A stiffening band 15 also formed preferably of buckram or the like constitutes another mem-

40 ber of the stiffening structure of the pad and has a V-shaped slit 16 extending thereto from one edge.

A stiffening band 15 also formed preferably of buckram or the like constitutes another mem-

45 ber of the stiffening structure of the pad and has a V-shaped slit 16 extending thereto from one edge.

A stiffening band 15 also formed preferably of buckram or the like constitutes another mem-

50 ber of the stiffening structure of the pad and has a V-shaped slit 16 extending thereto from one edge.

A stiffening band 15 also formed preferably of buckram or the like constitutes another mem-

55 ber of the stiffening structure of the pad and has a V-shaped slit 16 extending thereto from one edge.

A stiffening band 15 also formed preferably of buckram or the like constitutes another mem-

60 ber of the stiffening structure of the pad and has a V-shaped slit 16 extending thereto from one edge.

A stiffening band 15 also formed preferably of buckram or the like constitutes another mem-

then applied to the member 1 and drawn taut in a transverse direction prior to being stitched thereto. Thus it provides a snug fit on the top surface of the stiffening member 1. The edges of the slits 9 are fastened together so as to give the member an abrupt upwardly curved effect along the base edges of the members and by subsequently inturning the slit edge of the member 17 and stitching it to the bottom of the member 8, a smooth top finish will be provided and the parts will be held against spreading along the slit portions thereof. The final step in the assembly of the parts comprises stitching the lining 20 to the side edges of the members 1 and 6 after which a dart 21 is formed in the lining. This will cause the lining to be shortened and will cause the stiffening members and the top or cover member 17 to bow transversely. Thus the resultant pad will consist of the lining 20 shortened by the dart 21 and the upwardly bowed stiffening members joined at their margins to the lining as indicated at 22. If the slit ends of the stiffening members are drawn together and secured as explained, said members will be bowed not only from side to side but will also be provided with an abrupt upwardly extended base portion 23 merging into a gradually curved portion 23 leading to the apex 24 of the pad. The space between the stiffening members and the lining 20 is hollow and the band 15 as well as the stiffening members to which it is attached cooperate to produce a bridge effect which will stand up under the ordinary weight of the shoulder portion of a garment. Obviously by increasing or reducing the size of the dart, the bow in the pad can be increased or reduced. Thus the pad is adjustable readily to increase or reduce the height of the shoulder of the garment resting on the pad.

The pad can be attached to the garment G by any suitable means as by snap fasteners 25 located at the corner portions of the pad.

What is claimed is:

1. A shoulder pad for outer garments including superposed connected thicknesses of stiffening fabric, one of said thicknesses having an elongated V-shaped slit the edge portions of which are drawn together and stitched to the other thicknesses of said material, there being V-shaped slits extending into the base portions of the stiffening materials, the edge portions of said slits being gathered together, the covering material fitted snugly upon the stiffening material and having inturned edges stitched to the stiffening material, the edges of the slits in the base portion of the stiffening material being stitched together thereby to impart to the pad an abrupt upwardly curved contour along the said base portion, and a lining secured to the side portions of the stiffening members, there being a dart in the lining for holding the lining taut and maintaining a transverse bow in the stiffening members whereby said members are held spaced from the lining between their edges.

2. A shoulder pad for outer garments including superposed connected thicknesses of stiffening

fabric, one of said thicknesses having an elongated V-shaped slit the edge portions of which are drawn together and stitched to the other thicknesses of said material, there being V-shaped slits extending into the base portions of the stiffening materials, the edge portions of said slits being gathered together, the covering material fitted snugly upon the stiffening material and having inturned edges stitched to the stiffening material, the edges of the slits in the base portion of the stiffening material being stitched together thereby to impart to the pad an abrupt upwardly curved contour along the said base portion, a band of stiffening material extending transversely of and stitched to the stiffening members close to the slits in said members, and a lining secured to the side portions of the stiffening members, there being a dart in the lining for holding the lining taut and maintaining a transverse bow in the stiffening members whereby said members are held spaced from the lining between their edges.

3. A shoulder pad for outer garments including superposed connected members of thin stiffening fabric having slits therein, the side edges of each slit being held together, thereby to provide a thin and relatively flexible pad of substantially dome-shaped configuration, and a taut lining having its marginal edges connected to opposed marginal edges of the stiffening members, said lining being so formed as to have when connected to the stiffening members a smaller distance between its edges than the normal distance between the edges of the stiffening members, whereby to determine the transverse contour of the pad, and to define an open space between the lining and the superposed stiffening members.

4. A shoulder pad for outer garments including superposed thicknesses of stiffening fabric, one of said thicknesses having an elongated V-shaped slit the opposed edges of which are held together, thereby to impart a transverse curvature to the material, there being V-shaped slits extending into the base portion of each thickness of material, said edges being joined to impart an abrupt upward curve to the base portions of said thicknesses, a lining secured at its marginal edges to opposed marginal edges of the superposed thicknesses, said lining being otherwise non-connected to the superposed thicknesses and a dart in the lining adapted to maintain said lining taut whereby to hold the connected thicknesses of material in an upwardly bowed configuration, said lining being spaced apart from said thicknesses intermediate its connections thereto.
